(57) **CLAIM**

The ornamental design for a scratching post as shown and described.

DESCRIPTION

FIG. 1 is a front elevation view of a scratching post, showing my new design;

FIG. 2 is a rear elevation view thereof;

FIG. 3 is a left side elevation view thereof;

FIG. 4 is a right side elevation view thereof;

FIG. 5 is a top plan view thereof;

FIG. 6 is a bottom plan view thereof;

FIG. 7 is a perspective view thereof; and,

FIG. 8 is a further left side elevation view thereof with an environmental structure shown in broken lines.

The broken lines in the drawings illustrate portions of the scratching post that forms no part of the claimed design. In FIG. 8, the broken lines illustrate environmental structure that form no part of the claimed design.

1 Claim, 8 Drawing Sheets
